Gunnar P. Peterson
BY *[Signature]* ATTORNEY.

UNITED STATES PATENT OFFICE.

GUNNARD P. PETERSON, OF NAUGATUCK, CONNECTICUT, ASSIGNOR TO THE RISDON MANUFACTURING COMPANY, OF NAUGATUCK, CONNECTICUT, A CORPORATION OF CONNECTICUT.

REEL.

Application filed March 16, 1922. Serial No. 544,103.

To all whom it may concern:

Be it known that I, GUNNARD P. PETERSON, a citizen of the United States, residing in Naugatuck, Connecticut, have invented 5 the following described Improvements in Reels.

My invention relates to the spools or reels for the paper records of player-pianos and like uses and its object is to provide inexpensive end pieces for such reels that are extremely durable in use and practically proof against disfigurement from accidental causes, as for example, the dropping of the reel when loaded with a heavy paper record.

In the accompanying drawing, Fig. 1 shows a reel embodying my invention, the end pieces being in section. Figs. 2, 3 and 4 show the separated parts of an end piece. 20 Fig. 5 shows the same parts assembled and in elevation, and Fig. 6 shows a modification.

The reel shown in Fig. 1 comprises a cylindrical body of wood or composition, made 25 tubular or recessed at its ends for attachment to the hubs of the end pieces, which are marked 2 and 3, and which are identical in structure except that the piece 3 at the left hand end is provided with a driving slot 6 while the other has no such slot. Their function is to provide the flanges 30 at the ends of the reel to guide and protect the paper record wound on the body and also to provide the bearing seats or journal means by which the reel is supported for 35 rotation in the piano. Each of these end pieces 2 and 3 comprises metal end members and a body or filler of a moldable material made of or having a base of rubber shoddy, but any other material which is 40 moderately rigid and preferably somewhat elastic when molded and not easily fractured may be substituted. In the preferred form, two separate outside metal 45 members 9 and 10 provide an enclosing metal casing and are crimped or otherwise united about the body or filler member 11. In the construction illustrated, the member 9 forms the surface of the inner side 50 of the flange of the end piece and is formed with a tubular boss, preferably closed at its end and serving as a hub 13 adapted to fit within the terminal recess of the spool body or to be otherwise secured thereto. 55 The other metal casing member 10 is se-

cured to the margin of the member 9 and is appropriately configured to form therewith an end piece of the size and thickness usual in music roll ends. Preferably each face member 10 is formed with a central 60 depression or socket 5, the end wall of which in the driving piece 3, is slotted at 6, to receive the driving key of the piano. Both metal members 9 and 10 may be stamped from flat sheet metal stock, and are joined 65 together in Figs. 1 to 5 by their oppositely disposed flanges 15 and 16, one of which, 16, fits within the other, 15, which is spun or crimped over it; obviously, however, this 70 construction of the metal casing is subject to modification. The filler 11 as already 75 stated, consists of a moldable plastic material and is designed to afford the strength and body required for the end piece while the outside pieces provide the metal or other 80 hard wearing-surfaces and bearings. The filler more or less fills and thereby reinforces the metal enclosure, in the instance shown, extending fully to the circumference 85 of the flange portion of the reel end and more or less into the hub 13, and also conforming to the contour of the casing members and thus permanently spacing and bracing the metal walls to prevent their being dented or crushed. As before stated, I have 90 found a compound having a rubber shoddy base, that is to say, a compound composed largely of rubber shoddy to be both effective and inexpensive and if desired, this 95 may be molded to final form prior to its assembly with the casing members. Such a filler is substantially proof against becoming loose and rattling. The centers of all the fillers 11 are recessed deeper than the depressions 5 to allow the necessary penetration 100 of the driving key into the slot 6 of the driving end piece; one size and shape of filler therefore serves for both ends.

In Fig. 6, the rim of the member 9 is 105 pressed inwardly, as shown, and the edge of the member 10 is turned into this annular groove which is preferably as deep as, or a little deeper than the thickness of the metal of the member 10, so that the edge of the latter is out of the way of the paper record as the latter is run on and off the reel. The filler 11, compressed between the members 9 and 10 (particularly at the bottom 110 of the inner convolutions 18 in the present instance), maintains the edges of the

metal members in contact elastically and hence prevents the loosening of the joint.

Claims:

1. A player-piano reel end-piece comprising a metal casing and a body of a plastic moldable material confined therein.
2. A player-piano reel comprising a cylindrical body and flanged end pieces therefor each comprising a thin sheet-metal ¹⁰ casing and a filler of a plastic moldable compound.
3. A player-piano reel end-piece comprising a thin metal hub member, a thin metal face member joined thereto, and a ¹⁵ filler and spacer consisting of a body of permanently plastic moldable material.
4. A player-piano reel end-piece comprising a thin metal casing consisting of a hub portion and a face portion joined there-²⁰ to, and a filler and spacer consisting of a rubber-base plastic moldable compound.
5. A player-piano reel end-piece comprising a thin metal casing consisting of a hub

member and a face member, the edge of one member being turned over the edge of the ²⁵ other to join the members, and an elastic filler and spacer compressed between said members and compensating for looseness at the joint.

6. A player-piano reel end-piece comprising a thin metal casing consisting of a hub member and a face member, one of said members having an annular convolution and the edge of one of said members being turned over the edge of the other to join ³⁰ the members, and an elastic filler and spacer contained between said hub and face members and compressed between the bottom of ³⁵ said convolution and the other of the two members to maintain the join between the two members tight and compensate for looseness at said join.

In testimony whereof, I have signed this specification.

GUNNARD P. PETERSON.
